RECOIL ABSORBER FOR FIREARMS

Norbert Jules André Galliot, Vaucresson, and
Jeanne Adrienne Victorine Anna Chable, Paris,
France

Application July 28, 1937, Serial No. 156,226
In Switzerland August 3, 1936

6 Claims. (Cl. 89—14)

The present invention relates to "muzzle brakes" or recoil absorbers for firearms, of the type including one or several convergent divergent nozzles, fixed to the end of the barrel of the arm, coaxially therewith, and intended to increase the kinetic energy of the gases, which are subsequently deviated and discharged outwardly by means of a stationary system of blades, either simple or multiple, produced by the revolution, about the longitudinal axis of the arm, of one or several arcs of curves having their concavity turned toward the rear of the arm. The energy of the gases which react against this system of blades is utilized for exerting a tractive force in a direction opposed to that of the force producing the recoil of the arm.

The invention is more especially concerned with a recoil absorber of this type made according to our French Patent No. 798,213, of February 13, 1935. In this recoil absorber, the gaseous streams, discharged in a rearward direction by the device, are given a rotative movement about the axis of the arm in such a manner that, under the action of the centrifugal force thus generated, they are urged in a direction transverse to said axis and strike a deflecting system at an angle so that they are deviated outwardly toward the front of the arm. This deflecting device is constituted by rings forming small frusto-conical cups having the large base located on the side of the front end of the arm and the cups are located one behind the other about the axis of the barrel of the arm.

The present invention relates to the mounting of these cup-shaped rings.

In the recoil absorber according to the above mentioned French patent, the various cup-shaped elements are rigid with one another so that their relative arrangement cannot be varied.

The essential feature of the present invention consists in making these cup-shaped elements in the form of individual rings slipped behind one another around the barrel of the firearm, with spacing means interposed between two consecutive rings for keeping the desired intervals between the successive rings, and means for holding all these elements applied against one another.

According to an embodiment of our invention, these rings are supported by ribs formed both on the outer surface of a sleeve fitted on the barrel and on the outer surface of the first nozzle.

According to this embodiment of the invention, each of the cup-shaped rings is provided, on its back face, with a removable spacing piece, constituting the spacing means above mentioned,

which permits varying the spacing of each of the cup-shaped elements with respect to the other cup-shaped elements.

Other features of the present invention will appear from the following detailed description of some specific embodiments thereof.

A preferred embodiment of the present invention will be hereinafter described, with reference to the accompanying drawing, given merely by way of example, and in which:

Fig. 1 is an external view, partly in axial longitudinal section, of the barrel of a firearm fitted with the recoil absorber according to the present invention;

Fig. 2 is a separate view of a ribbed sleeve, fitted upon the barrel, said sleeve being shown in cross section on the line 2—2 of Fig. 1;

Fig. 3 is a view on an enlarged scale of a detail of construction; and

Fig. 4 is a diagrammatical view explaining the operation of the recoil absorber.

In the drawing, reference character *a* designates the barrel of the firearm; *b* is a convergent-divergent nozzle screwed to the front end of the barrel; *c* and *d* are two other convergent-divergent nozzles, mounted ahead of the first one *b* and fixed to the envelope *e* as it will be hereinafter explained; *f* designates an inward flange, located ahead of the third nozzle *d* and provided with a ribbed cylindrical axial conduit *f*¹ for the passage of the projectile; *b*¹, *c*¹, *d*¹ designate annular conduits or grooves, generated by the revolution, about the longitudinal axis *x*—*x* of the arm, of the curved profile of the rear face *c*², *d*², *f*², turned toward the arm, of nozzles *c* and *d* and flange *f*, respectively. These conduits or blades *b*¹, *c*¹, *d*¹ constitute, so to speak, stationary blades. Nozzles *b*, *c*, *d* are rifled, in such manner as to impart to the gases passing through said nozzles, a rotary movement about the axis thereof. Preferably, the helical partitions or fins *b*³, *c*³, *d*³ of nozzles *b*, *c*, *d*, which correspond to the rifling of these nozzles, have a pitch in the same direction as that of the rifling of the bore of the barrel, and this pitch preferably varies in a gradual manner. In this case, the pitch of the partitions *b*³ of nozzle *b* is slightly smaller than that of the riflings of the bore of the barrel. The pitch of the partitions *c*³ is smaller than that of the partitions *b*³, and the pitch of the partitions *d*³ is still smaller than that of the partitions *c*³ of the second nozzle *c*.

The gases, which are thus given an extremely rapid movement of rotation about the axis *x*—*x* of the arm, escape through blade systems *b*¹, *c*¹, *d*¹.

d^1 and are deflected and discharged toward the rear, passing between streamlined helical partitions h, i, j provided on the outer faces of nozzles b, c, d . The rear part of envelope or casing e is 5 provided with screw threads in its inner wall, adapted to engage corresponding screw threads provided on the outer edges of the ribs or partitions h of the first nozzle b . As for nozzles c and d , they are each made of two parts screwed in 10 each other, to wit an external part integral with casing e through partitions i and j , and an internal part forming the nozzle proper. These partitions h, i, j have a pitch depending upon the pitch of the riflings of the bore of the barrel, in 15 such manner as to give the minimum resistance to the helical movement of the gaseous streams leaving the recoil absorber and to maintain it and even accelerate it, if possible. But this pitch of the partitions is opposed to that of the riflings of 20 the bore.

The envelope e of the recoil absorber may, as shown by the drawing, be provided with a plurality of small ports e^1 , suitably inclined, through which a portion of the gases issuing from the 25 blade systems b^1, c^1, d^1 is discharged into the atmosphere.

The gaseous streams leaving the recoil absorber pass along deep helical partitions or ribs k^1 provided on the outer surface of a sleeve k fixed to 30 barrel a . Preferably, this sleeve is made of a light alloy of high thermic conductivity and the thermic expansion of which approximates that of the metal of the barrel, for instance an aluminum alloy containing a high percentage of silicon.

These helical partitions or ribs have a pitch opposed to that of the riflings of the barrel bore, and are shorter at the origin, that is to say at the front. Preferably, this pitch varies gradually, being shorter toward the rear. These helical partitions or ribs maintain and accelerate the movement of rotation of the gaseous streams about the axis $x-x$ of the arm. Under the influence of the centrifugal force which results 35 therefrom, these gaseous streams are driven away from their initial path and move in a direction substantially transverse to the axis $x-x$ of the arm.

These gaseous streams thus strike deflecting parts which are constituted by rings in the form of small frusto-conical cups l the large base of which is located toward the front of the arm. These cup-shaped elements, which are small and numerous, are merely slipped, behind one another, about the barrel of the arm, on the ribs k^1 of sleeve k . They are kept in position in the following manner. The first cup-shaped element, at the front end, bears upon the rear edge of the envelope e of the recoil absorber proper. The last cup-shaped element, at the rear, bears upon an abutment piece m , fixed to the barrel a of the arm, between the latter and the rear end of sleeve k . This abutment piece m is provided with a recess m^1 which constitutes an expansion chamber for the gases.

On the periphery of the back face of each cup-shaped element, from place to place, are secured, in a removable manner, through screws l^1 , blade-shaped pieces l^2 , against which bears the next cup-shaped element, in such manner as to provide the desired spacing between the cup-shaped elements. With this arrangement, it is possible easily to adjust this interval between the cup-shaped elements, either by replacing these spacing blades l by others of a different size and

profile, or, more simply, by filing off the spacing parts so as to obtain the desired spacing of the cup-shaped elements, according to the kind of arm that is employed, its bore and various other conditions.

These spacing blades l may be disposed parallel to the axis of the arm or in a helical arrangement.

The cup-shaped elements are preferably given, as shown, a lens-shaped transverse section.

The operation is the following. The gases discharged from the system of the blades of the recoil absorber and moving with a quick rotary motion about the axis $x-x$ of the arm under the effect of the rifling of the barrel bore, of the internal helical partitions b^3, c^3, d^3 of nozzles b, c, d , of the external helical partitions h, i, j of these nozzles, and of the helical ribs k^1 of sleeve k , are, under the effect of the centrifugal force thus produced, projected outwardly, in a direction 15 transverse to this axis $x-x$, and they strike the internal faces of cup-shaped elements l . The latter reflect them toward the front of the arm. As shown in Fig. 4, the cup-shaped elements l are spaced apart from one another a distance 20 such that a portion of the gaseous stream, projected at u , behind the rear edge of a cup-shaped element, meets another portion of this gaseous stream, projected at v against the internal face of the next cup-shaped element, which deviates 25 this portion of the gaseous stream. This meeting of the gaseous streams produces eddies in the gases. This second portion of the gaseous stream drives the first portion toward the front part of 30 the arm.

The gases, leaving the recoil absorber, are thus divided into a great number of streams, which are deviated toward the front, and which cannot injure the crew of the arm, as might take place, especially in the case of arms of large bore.

The construction above described permits a very easy and economical assembly, adjustment, and disassembly. The structure is very strong. In order to take it to pieces, it suffices to unscrew the envelope or casing (which carries nozzles c and d) from the partitions or ribs h of the first nozzle b , and rings l can then be removed by merely causing them to slide along the ribs k^1 of sleeve k .

The cup-shaped elements can be kept in position on sleeve k in any suitable manner other than that shown, for instance by screwing on an external system of threads provided on the ribs k^1 of sleeve k . The adjustable spacing between the cup-shaped elements can also be obtained in any suitable manner. The cup-shaped elements 50 can also be maintained in position by a slight conicity of the ribs k^1 of sleeve k , the sizes of the apertures in the cup-shaped members then varying from one cup-shaped element to the next one.

The ribs k^1 which support the cup-shaped elements l , instead of being provided on a sleeve fixed to the barrel a of the arm, might be formed directly on said barrel. Instead of being helical, these ribs k^1 might be parallel to the longitudinal axis of the arm. As a matter of fact, it has been found that the pitch of the ribs must be the longer as the length of the apparatus is greater. Therefore, this pitch can be infinitely great under certain circumstances. In this case, the gases are projected against the cup-shaped elements by the centrifugal force imparted thereto in their rotary movement due to the rifling of the bore and to the internal helical partitions b^3, c^3, d^3 of nozzles b, c, d .

In a general manner, while we have, in the

above description, disclosed what we deem to be practical and efficient embodiments of the present invention, it should be well understood that we do not wish to be limited thereto, as there might be changes made in the arrangement, disposition, and form of the parts without departing from the principle of the present invention as comprehended within the scope of the appended claims.

10. What we claim is:

1. In connection with a firearm having a barrel, a recoil absorber which comprises, in combination, at least two convergent divergent nozzles fixed in series to the end of said barrel coaxially therewith, a system of blades carried by said nozzles for deflecting the gases issuing from said barrel into a rearward direction and rotating them about the axis of said barrel, a plurality of frusto-conical rings each having its large base turned toward the front of the firearm mounted around the axis of said barrel at the rear of said nozzles so as to be struck by the gases thus deflected rearwardly, said rings being individually slipped around said barrel, and means for keeping said rings in position.
2. In connection with a firearm having a barrel, a recoil absorber which comprises, in combination at least two convergent divergent nozzles fixed in series to the front end of said barrel coaxially therewith, a system of blades carried by said nozzles for deflecting the gases issuing from said barrel into a rearward direction and rotating them about the axis of said barrel, helical ribs carried by said nozzles on the outer periphery thereof, a tubular casing surrounding said ribs, a sleeve fitted on the front end of said barrel, including ribs in line with the first mentioned ribs, a plurality of frusto-conical rings each having its large base turned toward the front of the firearm individually slipped on said ribs around the axis of said barrel, so as to be struck by the gases thus

deflected rearwardly, distance members interposed between two consecutive rings, and means for holding said rings with their distance members applied against one another.

3. In connection with a firearm having a barrel, a recoil absorber which comprises, in combination, at least two convergent divergent nozzles fixed in series to the front end of said barrel coaxially therewith, a tubular casing surrounding said nozzles, deflecting surfaces carried by the second nozzle and the front end of said casing for deflecting the gases issuing from the first nozzle into a rearward direction, blades carried by said nozzles, forming helical ribs between the outer peripheries of said nozzles and said casing, for rotating these deflected gases around the axis of said barrel, a sleeve fitted on the front end of said barrel, including ribs prolonging the first mentioned ribs, a plurality of frusto-conical rings each having its large base turned toward the front of the firearm individually slipped on said ribs at the rear of said casing, so as to be struck by the rearwardly deflected gases, spacing members carried by each ring for cooperating with the next one, and means for holding said rings with their spacing members applied against one another.

4. A recoil absorber according to claim 3 in which each of said spacing members is removably carried by the corresponding ring.

5. A recoil absorber according to claim 3 in which each of said spacing members is removably carried by the back side of the corresponding ring.

6. A recoil absorber according to claim 3 in which each of said rings has in axial section the shape of a biconvex lens.

NORBERT JULES ANDRÉ GALLIOT.
